OIL CONDITIONER CARTRIDGE

Charles A. Winslow, Laurence L. Moore, and William G. Nostrand, Oakland, Calif., assignors to Winslow Engineering Co., Oakland, Calif., a partnership consisting of Charles A. Winslow, Catherine B. Winslow, Laurence L. Moore, and William G. Nostrand

Application January 25, 1943, Serial No. 473,476

4 Claims. (Cl. 210—187)

This invention relates to oil purifying or oil conditioning apparatus for use, for example, with internal combustion engines, and pertains particularly to a filtering cartridge member therefor. It is in the nature of an improvement over the inventions shown and described in the copending applications of Charles A. Winslow and Laurence L. Moore, Serial No. 258,653 and Serial No. 430,749, filed, respectively, February 27, 1939, and February 13, 1942.

The inventions of said applications have proven highly satisfactory and are in extensive use, but by reason of the scarcity of certain materials, due to the economic situation brought about by war demands, we have been confronted with certain manufacturing difficulties which the present invention is designed to overcome.

To that end, we have developed a cartridge for use in a suitable holder, which dispenses with the use of woven fabric and metal and employs paper or fiberboard elements. No metal parts need be used in the cartridge. Therefore, the filtered oil is not deleteriously affected by the corrosive action normally produced by the continued action of oil on metal.

Our inexpensive, replaceable cartridge enables highly efficient filtration of oil, all as will more fully appear hereinafter.

Having reference to the accompanying drawing, wherein similar characters of reference represent corresponding parts in the several views:

Fig. 1 is a longitudinal, sectional view of one application of use of the cartridge.

Fig. 2 is a longitudinal, sectional view of the cartridge assembly.

Fig. 3 is a cross-sectional view, taken on line 3—3 of Fig. 2.

Fig. 4 is a longitudinal, sectional view of a modified form of the cartridge assembly.

Fig. 5 is a cross-sectional view, taken on line 5—5 of Fig. 4.

Fig. 6 is a fragmentary view of a perforation in the tube 3.

Fig. 7 is a fragmentary view of a perforation in the tube 2 or 2'.

In our improved cartridge, we employ a central tubular core 2, of fiber or cardboard, of a length corresponding to the length of the finished cartridge. Concentric with tube 2 is a similar and larger fiber tube or cylinder 3, separately spaced from tube 2 and of a diameter corresponding to that of the finished cartridge. In length the tube 3 is slightly shorter than tube 2 for reasons shortly to appear. Both tubes 2 and 3 are provided with numerous respective perforations 4—5 55

for the passage of the oil undergoing filtration.

The ends of the outer cylinder 3 are closed by paper caps or covers 6, which are centrally perforated to have a snug fit over the slightly protruding ends of the central tube 2. By means of the caps 6 the concentricity of the two tubes is maintained at all times. The space between the two tubes is filled with a compacted mass of suitable filtering material 7, preferably of cotton waste and wood shavings.

After the filtering material has been inserted and the caps 6 placed in position, fiber washers 8 are pressed over the exposed ends of tube 2 and down tight against the caps 6 to provide reinforcement at these points. A tapered, hollow plug 9, preferably made of wood, with a peripheral flange 10, is then forced in at each end of tube 2 to expand the ends of the tube 2 with the flange 10 resting clamp-fashion against a respective washer. The wooden plugs have such a friction fit with the inner tube that when they are pressed inwardly they hold the assembled parts firmly together. The cartridge is then ready for use.

It is understood that the tubes 2 and 3, although of pulp fiber, have sufficient inherent rigidity that they will maintain their shape and position at all times under working conditions.

The mode of use is illustrated in Fig. 1, in which 30 11 represents a container or holder similar to that described in the former applications aforesaid. The container 11 is in the form of a cylindrical shell to receive our improved cartridge. The shell has a central pipe 12, provided with 35 perforations 13, which forms an outlet for the oil after filtration.

The pipe is surrounded at one end by a coil spring 14, or other spacer means, on which rests a washer 14a, which latter, in turn, supports the cartridge which is slipped over the pipe 12 and is spaced therefrom by the thickness of the portions of the plugs 9 which telescope the paper tube 2 of the cartridge.

A removable cover 15 fits over the container 45 and is held in place by suitable means, as a screw threaded stud 16, fitting into the corresponding end of the pipe 12. The dirty oil to be filtered enters the container at 17 and passes up around the outside of the cartridge, whence it percolates through the perforations 5 in the outer shell or tube 3 of the cartridge and through the filtering material, escaping through perforations 4 in tube 2 and thence through perforations 13 into the outlet pipe 12, cleaned and reconditioned and ready for re-use.

Figs. 4 and 5 illustrate a simplified construction of our cartridge, wherein the cartridge construction is similar in principle to the embodiment previously described, but differs structurally in the design and assembly of tubular core 2' and cap members 6'. In the modification above referred to the caps 6' are provided with centrally disposed, inwardly turned flanges or hub portions 18 which are coaxial with tube 2' in order to fit snugly and concentrically within the ends of tube 2'. Caps 6' also have peripheral flanges 6^a which telescope with outer tube 3' when the parts are in operative position. In short, the caps 6' have each a pair of annular flanges 18 and 6^a which, respectively, have a snug sliding fit with tubes 2' and 3'. It is noted that tube 2' is preferably of slightly less length than tube 3' so that the caps may be fitted tightly against the ends of tube 3' and the filtering material. The hub portion 18 is preferably formed integrally with a cap and performs the function of a plug member 10 of Fig. 2 to hold the assembled parts together.

In Fig. 4 we have shown washers 19 positioned frictionally and concentrically with the hub portions 18 of caps 6' and disposed between the caps and the ends of tube 3'. It is obvious, of course, that the washers may be dispensed with and a direct connection between caps and the end portions of tube 3' can be effected. Preferably, but not necessarily, the ends of tube 2' are expanded outwardly slightly in order to insure an easy fit of the hub portions 18 into the ends of tube 2'.

The mode of use of the cartridge is substantially the same as illustrated in Fig. 2.

The perforations provided in the tubes 2, 2' and 3 are preferably punched toward the compacted mass of filtering medium. In this manner burrs 20 (Figs. 6 and 7) are formed and tend to hold the said filtering medium away from the perforations and thereby prevent pieces of the filtering medium from passing through the said perforations into the oil flow.

The expressions "cardboard," "fiber-board" and "pulp fiber" are intended to cover any suitable rigid fibrous paper product for the purpose indicated.

While the invention has been illustrated and described in certain detail of embodiment for illustrative purposes, it is not intended that the invention be limited thereto but that modifications and changes in details of construction may be incorporated within the spirit and scope of the appended claims.

We claim:

1. An oil conditioner element comprising a centrally disposed, perforated, rigid, pulp fiber, tubular core, a concentrically disposed outside per-

forated cylindrical casing of pulp fiber, a compacted filling of filtering material in the space between the core and casing, a paper cap closing over each end of the tube and casing to complete the enclosure of the filtering material, the caps having central openings coaxial with and of substantially equal diameter as the central tube, and a hollow plug fitting each end of the tubular casing and acting to expand the core and at the same time exert pressure endwise against the caps to clamp the parts together as a unitary structure.

2. An oil conditioner element comprising two concentrically arranged, spaced, pulp fiber tubes, each of which is perforated and of substantially equal length, a filtering material in the space between the tubes, pulp fiber caps fitting over the ends of the tubes to enclose the space containing the filtering material, the caps having central openings fitting over the inner tube and serving to center the tubes, a washer surrounding each projecting end of the inner tube and resting against the caps, and perforated non-metallic plugs frictionally fitting the ends of the inner tube and each plug having a peripheral flange to engage the adjacent washer, the plugs operative to clamp the parts together as a unit.

3. An oil conditioner element comprising a centrally disposed, perforated pulp fiber tube, a perforated pulp fiber casing tube concentrically spaced from said central tube, a compacted mass of filtering material in the space between the said tubes, pulp fiber caps fitted over the ends of said tubes and frictionally engaged with the end portions of said casing tube, said caps provided with centrally disposed bores in coaxial alignment with said central tube, and centrally perforated means frictionally fitting within the end portions of said central tube and adapted to hold the parts together and allow communication between said bores of said cap members and the said central tube.

4. An oil conditioner element comprising a centrally disposed, perforated, tubular core, an outer, perforated tube concentric with and spaced from the tubular core and of approximately the same length therewith, caps fitting over and spanning adjacent ends of the core and outer tube, each cap having two concentric flanges, one of which flanges engages frictionally and telescopically the outer tube and the other flange engaging frictionally and telescopically the inside of the core, and a filtering medium in the annular space enclosed between the core and outer tube and caps.
